UNITED STATES PATENT OFFICE.

ERNEST C. WINGIRE, OF MINNEAPOLIS, MINNESOTA, ASSIGNOR OF ONE-HALF TO PETER J. N. MILLER, OF MILLER, SOUTH DAKOTA.

SELF-ANCHORING WINDLASS.

1,307,389.

Specification of Letters Patent. Patented June 24, 1919.

Application filed March 30, 1917. Serial No. 158,614.

To all whom it may concern:

Be it known that I, ERNEST C. WINGIRE, a citizen of the United States, residing at Minneapolis, in the county of Hennepin 5 and State of Minnesota, have invented certain new and useful Improvements in Self-Anchoring Windlasses; and I do hereby declare the following to be a full, clear, and exact description of the invention, such as 10 will enable others skilled in the art to which it appertains to make and use the same.

My invention has for its object to provide a combined windlass and anchor adapted for a great many different uses, and especially adapted to be carried in an automobile or motor-propelled vehicle and to be used in case the machine becomes mired or stuck, to draw the machine onto good road.

Generally stated, the invention consists 20 of the novel devices and combinations of devices hereinafter described and defined in the claim.

Because of the character of the device, and the manner in which it will anchor 25 itself under the drawing strain of the windlass, it is herein termed a self-anchoring windlass. The windlass is mounted on a suitable frame, preferably in the form of a longitudinally extended so-called back 30 rib that is provided at one end with a ground engaging fork or tine, and at its other end, with a pivoted head, to which head ground engaging thrust legs are pivoted for lateral movements. This arrangement 35 above generally outlined when combined with a windlass drum and cable applied as hereinafter described, produces a very highly efficient self-anchoring windlass which will anchor itself firmly, either to a 40 hard or soft roadbed, and which may be made of a small size and of light weight, and yet have sufficient pulling power to pull an automobile or truck out of any bad place in which it is likely to be stalled.

45 In the accompanying drawings which illustrate the invention, like characters indicate like parts throughout the several views.

Referring to the drawings,

Figure 1 is a plan view showing the im- 50 proved device;

Fig. 2 is a side elevation of the same ad-

justed for use to pull an automobile, for example, out of a hole or place where it is stuck; and

Fig. 3 is a side elevation illustrating the use of the device for stretching fence wires.

Describing first the construction when used as illustrated in Figs. 1 and 2, the numeral 4 indicates a tubular metal bar or pipe section which constitutes the back-frame member, and at its rear end, is provided with depending ground-engaging tines 5. Preferably there are two of these tines 5 arranged to constitute a fork projecting on opposite sides of the bar 4. A transversely extended yoke-like head 6 is pivotally connected to the upper or front end of the bar 4, by a transverse pivot bolt or pin 7. The opposite ends of the head 6 are bifurcated and the upper ends of folding legs 8 are pivotally connected thereto at 9. These legs 8 are preferably tubular and like the bar 4, advisably made of wrought iron or steel tubing.

To the intermediate portion of the back-rib or bar 4, a bearing bracket 10 is rigidly but adjustably secured. This bearing bracket 10 has a centrally located split sleeve that is adapted to be clamped onto the said bar 4 by nut-equipped bolts 11. The bracket 10 has depending arms 10^a in which a short transverse windlass shaft 12 is journaled. The said shaft, between the arms 10^a has a windlass drum 13, and at one end, has a worm gear 14. The worm gear 14 meshes with a worm 15 secured to a shaft 16 that is journaled and movable endwise in vertically spaced bearing lugs 10^b, one on the sleeve of the bearing bracket 10 and the other formed as a projection of one of the arms 10^a thereof. At its upper end, the worm shaft 16 has an angular shank 16^a to which a wrench, or the like, is adapted to be applied, so as to thereby rotate the worm and drive the windlass drum 13. The numeral 17 indicates a cable, one end of which is attached to and thereby wound upon the drum 13 and the other end of which is shown as provided with a hook 18 engageable with the tubular rear end of the back-rib or bar 4. A tackle block pulley or sheave 19 is applied to the intermediate

portion of the cable. This sheave 19 is journaled in a yoke 20 which, by means of an extended cable or connection 21, is adapted to be directly anchored to the automobile, 5 or other object to be pulled.

Figs. 1 and 2 show how the device is adapted to be set upon the ground or road and used as a combined anchor and power device. In this adjustment, the thrust legs 10 8 are preferably spread until their upper ends are stopped against the head 6, thus rendering the frame rigid. The inclination given to the said legs 8 may be varied. It is advisable to set the windlass drum as low 15 down as possible. In soft ground, the fork 5 will settle, of course, more than in hard ground, and hence, in setting the device in soft ground, the thrust legs 8 should be given greater inclination than when setting the 20 device on hard ground. Under the force of the pull on the cable, the fork 5 will enter the ground and the whole device will tend to move slightly forward. After the forks have entered the ground, the tension on the 25 legs 8 can be released and the free ends of the legs forced farther forward, so as to set the legs at less inclination to the ground and thereby throw the drum as close to the ground as practicable.

30 It is here important to note that with strain on the cable, half of the force will be applied to the hook 18, thereby pulling downward on the rear or lower end of the bar 4 and thus insuring good contact between the fork and the ground. This device will anchor itself either on very hard or soft ground. Under the cable drawing force, the lower hub of the worm 15 will be forced against the lower bearing lug 10^b and the 35 worm will be held in mesh with the worm gear 14. It will, of course be understood that the worm gears afford a self-locking device for the windlass drum. When the windlass drum is turned backward, the 40 worm will be raised toward the upper lug 10^b and here it should be noted that there is sufficient clearance between the two lugs 10^b to permit the worm to be raised entirely out of mesh with the worm gear. When 45 the worm is held in its raised position, the windlass drum may be freely rotated. Obviously, the said worm can be thus held in its raised or inoperative position simply by taking hold of the upper end of the worm 50 shaft 16 and holding the same in its uppermost position. As shown, the worm shaft 16 is provided with a perforation 16^b which, when the worm is raised will be just above the upper lug 10^b, so that by placing the pin 55 or nail, or the like, in the said perforation at such time, the worm will be held in its in-

operative position, without the use of the hands of the operator.

Fig. 3, as noted, shows the device used for pulling or stretching the wires of a wire 65 fence. In this use of the device, the fork-equipped end of the bar 4 is placed against the post *a* and the cable 17 is shown as connected by branch cables 17^a to a bar or wire clamp *b*, to which, in turn, the fence wires 70 *c* are attached and secured at their extended ends. In this use of the windlass, the spread ends of the legs 8 rest upon the ground.

In actual practice, the above described device has been found highly efficient for the 75 several purposes had in view. It is usually made of a comparatively small size and of a weight approximating twenty pounds, suitably designed to be carried under the seat of an automobile and serviceable for 80 pulling an automobile out of bad places.

When the device is out of use, the head or yoke 6 can be pivotally turned upside-down and the legs 8 folded together and against the back bar 4, so that the entire 85 device will occupy but very small space.

It will be noted that the back frame 4 is longer than the legs 8 and that the legs 8 are much longer than the depending prongs 5. This provides an arrangement in which, 90 regardless of the spread and the angle of the legs 8, the back frame 4 will always stand at an acute angle to the ground, or, stated in another way, the line of pull on the anchoring device will be at an acute angle to the 95 back frame. As the prongs enter the ground, the back frame will be moved into a slightly greater angle to the ground and to the line of pull, but will always be at an acute angle thereto, *i. e.*, an angle less than 100 forty-five degrees.

What I claim is:

In a device of the kind described, the combination with an oblique back frame, of a yoke-like head pivoted to the front end of the back frame for reverse turning movement past the front end thereof, a pair of legs pivoted to said head for transverse movement in respect to the back frame and arranged to be folded by a turning movement of said head into substantially parallel arrangement with the back frame, a bearing bracket mounted on the back frame, and a windlass drum journaled on the bearing bracket.

110 In testimony whereof I affix my signature in presence of two witnesses.

115 ERNEST C. WINGIRE.
